UNITED STATES PATENT OFFICE.

ELMER J. BUNDY, OF EAST PALESTINE, OHIO, ASSIGNOR TO THE McGRAW TIRE & RUBBER COMPANY, OF EAST PALESTINE, OHIO, A CORPORATION OF OHIO.

COLLAPSIBLE CORE.

1,307,435.

Specification of Letters Patent. Patented June 24, 1919.

Application filed March 17, 1919. Serial No. 283,059.

To all whom it may concern:

Be it known that I, ELMER J. BUNDY, a citizen of the United States, residing at East Palestine, in the county of Columbiana 5 and State of Ohio, have invented certain new and useful Improvements in Collapsible Cores; and I do hereby declare the following to be a full, clear, and exact description of the invention, such as will enable others 10 skilled in the art to which it appertains to make and use the same.

My invention relates to collapsible cores for the making and curing of pneumatic tires. Its object is to provide a core which 15 may be easily and quickly assembled or broken. The core has no detached or spare parts so that not only may it be quickly collapsed to be stripped from the tire, but also time and labor will be saved and the 20 core will have a longer life. To this end my invention comprises the parts and combinations of parts recited in the appended claims.

In the accompanying drawings Figure 1 25 is a plan view with the position of various parts indicated in dotted lines;

Fig. 2 is an edge view;

Fig. 3 is an enlarged broken detail of the 30 key-section for joining and locking together the several sections of the core;

Fig. 4 is a section on line 4—4 of Fig. 1;

Fig. 5 is a detailed plan of one of the locking hooks;

Figs. 6 to 11 are details.

35 In the drawings, 20 represents a key section, that is, the section which is first removed when the core is to be taken from the vulcanized tire. 21 and 22 are adjoining sections and 23 is the third section completing the core. At each end of the section 23 40 are dowel-pins, 24 and 25, taking into corresponding recesses 26 and 27 in the adjacent end of the sections 21 and 22.

28, 29, 30 and 31 represent a series of 45 hooks playing in corresponding recesses in the inner periphery of the core. Each hook is pivoted on a bolt which has an eccentric formed upon its shaft. The bolts are lettered in succession 32, 33, 34 and 35, beginning with that in section 23. These bolts 50 are shown in detail in Figs. 8 and 9, the eccentric boss on each bolt being indicated by the numeral 36, the bolts are adapted to pass through perforations in the core and 55 to be secured by a nut on the threaded end

of each bolt as illustrated in Fig. 4. Each of the bolts can be adjusted by applying a wrench to the head to take up any wear.

The engaging end of the hook takes over a bolt adapted to be secured to the core 60 in the manner just described with reference to the bolts 32—35, and, therefore, not necessary to illustrate specifically. These bolts in the succession before indicated are numbered 37, 38, 39, and 40. Each of these bolts also 65 bears an eccentric boss 41, as shown in Figs. 5 and 6, so that when a hook is turned on its pivot hinge by being hammered in at the hook end to engage the bolt 37, for example, the effect of the turning of the hinge perforation on the eccentric 41 will be to draw together the adjoining sections, leaving them still slightly separated as they are illustrated in Fig. 1.

In the key section 20, centrally located, 75 is a shaft 42 with a wrench-receiving head 43, and at the opposite end a head 44 carrying pins 45 and 46. The pin 45 also passes through one end of a link 47 on one side while the pin 46 passes through one end of 80 a link 48 on the other side. At the outer end of the links 47 and 48 are dowel-pins 49 and 50 secured to the links by bolts 51 and 52, and taking respectively into recesses 53 and 54 in the adjacent sections 21 85 and 22 of the core.

55 represents a tapering bolt with a threaded head which is screwed into a threaded seat in the top of the key-section 20, its opposite head forming a stop against 90 which presses the head 44 of the operating shaft 42.

When a wrench is applied to the head 43 the head 44 and the links 47 and 48 operate, as would a crank, wrist-pin and link connection, to simultaneously draw in the dowel pins 49 and 50 or to project them into the recesses 53 and 54.

To guide an inexperienced operator I provide a notch 56 in the key-section and a pin 100 57 on the shaft 42 so that the shaft can turn only within the limit determined by the period.

In breaking up the core, I insert the point of an appropriate tool in the notch 58 in 105 one of the hooks, having previously loosened the bolt 38, for example. This swings each hook upon its pivot so that they may be laid back, unlocking the sections 21, 22, and 23.

I now apply the wrench to the bolt head 110

43 and turn it as far as notch 56 and the pin 57 will permit, so that the dowel-pins 49 and 50 are drawn out of the recesses in the adjacent sections 21 and 22. This permits me to remove the key-section 20 and then the other sections.

In operating the bolts 32-35 to bring the eccentric boss 36 to bear against the operative curve of the corresponding hook I 10 find it expedient to provide means for determining the necessary turn to be given the wrench so that especially skilled or careful attention will not be required. To this end I provide slots 59, 60, 61 and 62 of appropriate length, one in the head of each of the bolts 37-40.

Pins 63, 64, 65 and 66 project from the core into these slots, each forming a stop, so that the operator simply turns the wrench 20 to cause a hook to turn upon the corresponding eccentric boss 41, drawing together the coupled sections, and stops when the opposite end of a slot, 59 for example, strikes the corresponding pin 63 projecting from the 25 core-section.

It should be observed that in addition to the functions I have enumerated the eccentric bosses on the bolts 32, 33, 34 and 35 take up any wear that may affect the hooks so 30 that at all times the sections may be drawn together in the same degree, and so that, finally, they may always be tightly joined.

It will be observed that sections 20 and 23 carry the pivot bolts for the hooks, and that 35 the bolts over which the engaging ends of the hooks take are at opposite ends of the sections 21 and 22. In assembling, the ends of sections 21 and 22 are brought up to opposite ends of section 23. Then when the 40 hooks 28 and 29 are turned over and hammered in, the immediate effect is to draw together the sections as shown. The key-section is put in place and the hooks 30 and 31 are hammered in, each hook taking over 45 a corresponding bolt and the eccentric boss on each bolt serving to draw together all the sections. The key-section is locked in place by the action of the shaft 42 and the crank and wrist-pin connection as described.

50 I claim,—

1. In a collapsible core, the combination with sections, of a hook pivoted in one section and a bolt with an eccentric bearing surface in the adjacent section with which 55 the hook engages.

2. In a collapsible core, the combination of sections, bolts secured in the sections, the

bolts having eccentric bearing surfaces formed upon them and hooks pivoted in one section and engaging a bolt in an adjacent 60 section to draw the sections together.

3. In a collapsible core, the combination with sections, of a hook, a bolt in one section having an eccentric bearing surface, the hook being pivoted upon one bolt and engag- 65 ing the other bolt.

4. In a collapsible core, a series of sections, hooks pivoted in one section and adapted to engage the adjacent section and to draw together the two sections, a key section, hooks pivoted to the key section and adapted to engage the adjacent sections to draw them and the key section together, and means for securing the key section to the adjacent sections. 70

5. In a collapsible core, the combination with a series of sections, of hooks, bolts passing through one end of some of the sections adapted to be engaged by the hooks and having an eccentric boss formed thereon, and a slot and pin device to limit the 75 turning of the bolt.

6. In a collapsible core, the combination of a shaft, links extending at a right angle from the shaft, dowel-pins connected to the 80 links, and a regulating pin screwed in to the section and opposing the head of the shaft.

7. In a collapsible core, a bolt with an eccentric surface to form a pivot for a securing hook and adapted to be operated by a 85 wrench to adjust the eccentric to take up wear.

8. In a collapsible core, the combination of a series of sections and a key section, a shaft located substantially central of the 90 key section, a crank and a wrist-pin mechanism operated by the shaft, and dowel-pins adapted to connect the key section and the adjacent sections and operated by the shaft and crank and wrist-pin con- 95 nection.

9. A collapsible core comprising four sections, one section having pivot bolts, hooks pivoted to the bolts at opposite ends of the section, two of the sections having bolts 100 which receive the engaging ends of the hooks, a key section having pivot bolts, hooks pivoted upon the bolts at opposite ends of the key section and adapted to take over bolts in the adjacent sections, and 105 means for finally securing together the other sections through the key section.

In testimony whereof I affix my signature.
ELMER J. BUNDY.
